VENTILATING DEVICE

Frank J. Scallon, Norwalk, Conn.

Application April 25, 1947, Serial No. 743,974

2 Claims. (Cl. 98—29)

1

This invention relates to ventilation of the spaces within building wall, floor and roof structures and more particularly to an improved rain and insect-excluding ventilating device for such spaces.

At present it is not customary to provide ventilation for the spaces between rafters, studding members and floor joists of buildings, which spaces are within the roof, wall and floor structures and are substantially closed, with the result that damp air leaking into such spaces deposits a portion of its moisture therein and this moisture tends to accumulate on the structural members, walls, and insulating material of the building causing such serious results as peeling of the paint, rotting of the joists, rafters and studding, deterioration of the plaster, warping of floors, and similar results familiar to users of wood buildings.

It is an object of the present invention to provide adequate ventilation for such spaces so that any moisture deposited therein will be taken up and removed, and to provide an improved ventilating device which will permit the free flow of ventilating air through such spaces while completely excluding the entry of rain or other precipitation, and insects therein.

A somewhat more specific object resides in the provision of an improved ventilating device for admitting air to relatively small spaces within building wall, roof and floor structures while excluding rain or other precipitation and insects from such places, which device is simple in construction, economical to manufacture, easy to install, and provides a neat and attractive appearance when installed in a building.

Other objects and advantages will become apparent from a consideration of the following description in conjunction with the accompanying drawings wherein:

Figure 1 is a perspective view of a fragmentary portion of a building showing the application thereto of ventilating devices illustrative of the invention.

Figure 2 is a transverse sectional view on an enlarged scale of a fragmentary portion of a building showing the application of the improved ventilating devices to the spaces between the floor joists of the building.

Figure 3 is a transverse sectional view of a fragmentary portion of a building showing the application of the improved ventilating devices to the eaves closure of the roof structure of the building.

Figure 4 is a front elevational view of an im-

2

proved ventilating device illustrative of the invention, a portion of the front wall being broken away to illustrate the application of the insect-excluding screen to the structure; and

Figure 5 is a transverse sectional view on the line 5—5 of Figure 4.

With continued reference to the drawings, the house illustrated in Figures 1, 2 and 3, has walls 10, a roof 11, floors 12, as indicated in Figure 2, and an extension provided with a flat roof 13.

The house may be of conventional construction and the walls may include spaced studding members 14 carrying an outside-wall-covering 15, and an inside covering 16. The wall-studding members are supported on floor joists 17 which are in turn supported on a sill 18 carried on a foundation 19. The spaces between the wall studs are closed at their lower ends by a supporting sill 20 and at their upper ends by a plate, not illustrated, and the ends of the spaces between the floor joists 17 are closed by the other wall covering 15, and suitable filler blocks 21.

The flat-roof portion 13 may be constructed similar to the floor structure with spaced joists 20 which carry the roof covering on their upper surfaces and have a ceiling covering attached to their lower surfaces, the ends of the spaces between these roof joists being closed by the end-wall covering of the building extension.

The roof 11 includes spaced rafters 22 with the roof covering 23 on the upper edges thereof and an internal wall-covering structure 24 underlying the rafters and secured to a portion of the lower edge of each rafter. The lower ends 35 of the spaces between the rafters are closed by an eaves-closure member 25, and the upper ends of these spaces open into an attic space within the upper part of the roof which space is ventilated by suitable gable louvers, such as the louver 26 shown in Figure 1.

The inner-wall coverings of the house are preferably formed of or provided with suitable insulating material and the floors and ceiling may also be insulated, if desired.

The spaces between the floor joists are suitably ventilated in accordance with the present invention providing circular apertures 26 through the outer-wall covering 15 and through the filler blocks 21, there being one such aperture at each end of each inter-joist space providing ventilating air passages into the spaces between the floor joists. The same method is used to provide ventilation of the spaces between the joists supporting the flat roof portion 13.

The spaces between the rafters 22 are venti-

lated by providing apertures 28 in the eaves-closure member 25 at the bottom end of these spaces, one such aperture being provided for each inter-rafter space to provide corresponding air passages for ventilating air to flow through the spaces between the rafters, the upper ends of these spaces being ventilated through the attic space and the gable louver 26.

The apertures 27 and 28 provide air passages leading into all of the spaces between the floor and roof joists and between the rafters. Similar apertures may be provided to constitute air passages leading into the spaces between the wall-studding members, if desired. Each of these air-passage apertures has secured therein a rain and insect-excluding ventilating device generally indicated at 30, and particularly illustrated in Figures 4 and 5.

The improved ventilating device is preferably formed from a single piece of thin non-corrosive material such as sheet aluminum or sheet copper. The mention of these materials, however, does not exclude the use of other suitable materials such as synthetic resin plastic, wood fibre, etc.

The improved ventilating device is simple and economical in construction and comprises a cylindrical sleeve portion 31, an end-wall 32 at one end of the sleeve portion, and a circular screen 33 of wire mesh positioned just inside of the end-wall 32. A marginal portion of the end-wall 32 extends somewhat beyond the cylindrical sleeve portion 31, as indicated at 34, and the corresponding end of the sleeve portion is externally flanged at 35, the edge of this flange being integral with the outer edge of the end-wall. This construction provides a double-walled circular flange around the end of the sleeve portion to which the end-wall is attached, and the circular screen 33 has its outer circumferential portion clamped between the walls of this double-walled annular flange to permanently secure the screen in operative position against the inner-side of the end-wall.

The end-wall is transversely slotted and has portions struck out to provide downwardly-inclined rain-excluding louvers 36, extending transversely across it. These louvers will effectively exclude the entrance of rain and other precipitation such as snow and sleet into the air passages leading to the spaces in the building roof, floor and wall structure, and the screen 33 effectively excludes the entry of insects, air-borne material such as leaf fragments, and sparks into the spaces.

The cylindrical sleeve portion 31 is provided with spaced longitudinal notches or slots 37 which permit the sleeve portion to contract to a limited extent when it is forced into the outer-end portion of an air-passage aperture in a building, and this sleeve portion is further provided with outwardly projecting detents 38 between the slots 37 which detents engage the wall of the corresponding aperture to firmly secure the ventilating devices in operative position in the building. The annular flange at the end-wall end of the cylindrical sleeve overlies the building surface at the outer end of the aperture receiving the ventilating device and definitely positions the ventilating device in the aperture

and provides a finished flange around the outer end of the device.

The use and advantages of the disclosed ventilating device are believed to be entirely obvious from the above description. It is also apparent that the device is neat and attractive in appearance, and does not, in any way, detract from the appearance of a building in which such ventilating devices are installed, and it is also apparent that the devices are so simple and economical in construction that the advantages provided by them may be obtained without any appreciable increase in the cost of building construction.

What is claimed is:

- 15 1. A device for providing ventilation to the spaces formed between the walls of buildings comprising a cylindrical sleeve portion having circumferentially spaced longitudinal slots adjacent one end thereof, said sleeve portion being provided with inclined detents disposed between said slots, an end wall formed integrally with the other end of said sleeve portion and provided with a plurality of transverse louvers, the peripheral edge of the sleeve portion adjacent 20 said end wall being curved outwardly to form in conjunction with the latter a double-walled annular flange, and a circular wire mesh screen positioned within said other end of the sleeve portion and having its circumferential edge secured between the walls of said double-walled 25 annular flange.
- 20 2. A device for providing ventilation to the spaces formed between the walls of buildings comprising a cylindrical sleeve portion having circumferentially spaced longitudinal slots adjacent one end thereof, said sleeve portion being provided with inclined detents disposed between said slots, an end wall formed integrally with the other end of said sleeve portion and provided with a plurality of transverse louvers, the peripheral edge of the sleeve portion adjacent 25 said end wall being curved outwardly to form in conjunction with the latter a double-walled annular flange, and means positioned within 30 said other end of the sleeve portion and secured between the walls of said double-walled annular flange whereby air passing through said louvers is removed of foreign particles.
